US00D831835S

(12) **United States Design Patent** (10) **Patent No.:** **US D831,835 S**
(45) **Date of Patent:** **** Oct. 23, 2018**

(54) **SKIN CLEARING AND TONING DEVICE**

(71) Applicant: **Carol Cole Company**, Vista, CA (US)

(72) Inventors: **Carol Cole**, San Marcos, CA (US);
Tera Peterson, Carlsbad, CA (US)

(73) Assignee: **Carol Cole Company**, Vista, CA (US)

(**) Term: **15 Years**

(21) Appl. No.: **29/582,081**

(22) Filed: **Oct. 25, 2016**

Related U.S. Application Data

(60) Continuation of application No. 29/512,088, filed on Dec. 16, 2014, now Pat. No. Des. 770,635, which is a division of application No. 29/419,770, filed on May 1, 2012, now Pat. No. Des. 722,383.

(57) **CLAIM**

The ornamental design for a skin clearing and toning device, as shown and described.

DESCRIPTION

FIG. 1 is a perspective view of a skin clearing and toning device of the present invention;

FIG. 2 is a front elevational view of the skin clearing and toning device shown in FIG. 1;

FIG. 3 is a rear elevational view of the skin clearing and toning device shown in FIG. 1;

FIG. 4 is a left side elevational view of the skin clearing and toning device shown in FIG. 1, the right side view being a mirror image of the illustrated view;

FIG. 5 is a top plan view of the skin clearing and toning device shown in FIG. 1; and,

FIG. 6 is a bottom plan view of the skin clearing and toning device shown in FIG. 1.

The broken line showing of a skin clearing and toning device is included for the purpose of illustrating portions of the article and forms no part of the claimed design.

1 Claim, 3 Drawing Sheets
